UNITED STATES PATENT OFFICE.

GEORGE W. LAWRENCE, OF EAU CLAIRE, WISCONSIN.

DESIGN FOR A REMOVABLE SIDE FLUE FOR REFRIGERATORS.

SPECIFICATION forming part of Design No. 23,105, dated March 6, 1894.

Application filed January 13, 1894. Serial No. 496,822. Term of patent 14 years.

To all whom it may concern:

Be it known that I, GEORGE W. LAWRENCE, a citizen of the United States, residing at Eau Claire, in the county of Eau Claire and State 5 of Wisconsin, have invented certain new and useful Improvements in a Design for a Removable Side Flue for Ice-Chambers of Refrigerators; and I do hereby declare the following to be a full, clear, and exact description of the 10 invention, which will enable others skilled in the art to which it appertains to make and use the same.

My present invention relates to a new design for a removable side flue for the ice 15 chambers of refrigerators.

A perspective view of a side flue embodying my new design is shown in the accompanying drawing.

The leading features of my design consist 20 in a removable side flue, rectangular in shape, and with a beveled lower edge and having two ribs on the back thereof, and a flattened hook or projection extending up from each of said ribs.

25 A, is the main portion of the side flue, of the general rectangular shape shown. In

practice, this portion A, is covered on its front with sheet metal B, which extends below the bottom thereof, and forms the thin projection C.

D, D, are ribs on the back of the body A, which extend the entire length of the said body and are parallel with the sides thereof. The lower edge of the body A, is beveled at 30 a, and the lower end of each rib D, is beveled 35 at b, as shown.

E, is a thin projection which extends up from each rib D, and which is provided with a slot c, therein whereby the said slotted projections will constitute hooks by means of 40 which the side flues may be hung within the ice chambers of refrigerators.

What I claim is—

The design for a removable side flue for the ice chambers of refrigerators herein shown 45 and described.

In testimony whereof I affix my signature in presence of two witnesses.

GEORGE W. LAWRENCE.
